UNITED STATES PATENT OFFICE.

DAVID E. TINGLEY, OF MARSHALL, ILLINOIS.

CONCRETE-MOLD.

988,049.

Specification of Letters Patent. Patented Mar. 28, 1911.

Application filed July 1, 1910. Serial No. 569,857.

To all whom it may concern:

Be it known that I, DAVID E. TINGLEY, a citizen of the United States, residing at Marshall, in the county of Clark and State 5 of Illinois, have invented certain new and useful Improvements in Concrete-Molds, of which the following is a specification.

My invention relates to certain new and useful improvements in concrete molds, and 10 particularly to molds for hollow concrete, masonry constructions for building conduits, arches, sewers and other structures of this general class.

The object of my invention is to provide 15 a mold in which both its height and width may be readily adjusted for the purpose of building structures of various sizes.

A further object of my invention is to provide a structure of this character which 20 is simple in construction and composed of few parts, and one in which the adjustments may be readily made and the molds readily placed in position for use and afterward removed therefrom.

25 With these and other objects in view my invention consists in certain constructions, combinations and arrangements of parts, the preferred form of which will be first described in connection with the accompanying drawings and then the invention particularly pointed out in the appended claim.

Referring to the drawings wherein I show several forms of my invention and wherein the same part is designated by the same reference numeral wherever it occurs, Figure 1 is an end view of one form of one section of my mold; Fig. 2 is a similar view of a slightly modified construction; Fig. 3 is a similar view of another modification; Fig. 40 4 is a similar view of a still further modification; Fig. 5 is a detailed view showing one form of connection between the parts of the mold; Fig. 6 is a perspective view of the end portion of one of the L-bars forming the mold, and Fig. 7 is a side of one of the clips carrying a locking pin for locking the parts of the mold together.

Referring to Fig. 1, 7 and 8 designate a pair of L-bars which are adapted to have 50 their ends joined together to form the roof of the mold, these bars being bent downwardly at 9, 10 to form the sides of the mold. 11, 12 are a pair of bars adapted to have their ends joined together to form the 55 floor of the mold, the bars 11 and 12 being provided with the upwardly extending ends

13 and 14, which are adapted to be connected with the portions 9 and 10 to form the sides of the mold. The end portions of the pair of bars 7 and 8 and the pair of bars 11 and 12 overlap, and the overlapping portions are provided with a plurality of holes 15 which are adapted to be brought into registry with each other, and 16 are pins carried by clips 17, the pins being 60 adapted to be inserted through the openings 15 to connect the bars 7 and 8 together with the clips engaging the adjacent surfaces of the two bars 7 and 8 to hold the pins in position, the clips 17 being of the form shown 70 in Fig. 7. The down-turned end portions of the bars 7 and 8 and the up-turned end portions of the bars 11 and 12 are similarly adjustably connected together by providing similar openings 15 therethrough adapted 75 to be engaged by pins 16 carried by clips 17.

From the foregoing description taken in connection with the drawings it will be seen that both the height and width of the mold may be adjusted, and that if for instance the holes 15 are placed in the bars a foot apart sizes varying a foot from each other either in height, width, or both, may be formed.

In order to brace the molds against the 85 wall of cement I preferably provide at each end of the mold a pair of bars 18 pivoted together intermediate their ends by means of the pivot 19, the ends of the bars being also perforated and being adapted to be 90 secured by means of pins 20 to the bottom and end portions of the mold. The pins 20 pass through openings 21 in the L-bars, so that by providing a plurality of these openings the mold may be braced in its various 95 positions of adjustment. I also preferably provide a bar 22 which is adapted to be pinned to the central portion of the mold, a plurality of these bars being used one for each height to which the mold may be adjusted.

Referring now to Fig. 2, the bars 7 and 8 are formed with the down turned ends 9 and 10 and the overlapping ends of the bars are connected together in the manner just described in connection with Fig. 1. Instead of the bars 11 and 12, however, to form the floor a pair of bars 21, 22 as illustrated which, in the form shown, are curved, these bars are provided with openings 23, and the 110 overlapping ends of the bars are connected together by means of pins 16 carried by

clips 17 in the manner hereinbefore described. Secured to the ends of the bars 21, however, as by pins 24, are the straight sections 25 formed of L-irons, said sections 5 being provided with perforations 26, through which pins 27 may be passed to secure the bars to the down-turned ends 9 and 10. By placing pins through various combinations of the openings in the ends 9 and 10 and the bars 25 the height of the mold 15 may be adjusted. The roof of the arch is shown as braced by means of the bars 28, through one end of which pass the pins 27, the other ends being connected by means of pins 29 to the bars 7 and 8. By providing a series of perforations 30 in the bars 7 and 8 for the pin 29 to engage the bar a single length of bar 28 may be used for the various 20 adjustments of the height of the mold. I also provide a central support 22 as is used in connection with the form shown in Fig. 1.

In the form of invention shown in Fig. 3 the bars 21, 22 shown in Fig. 2 are used together with the end bars 25, 25 to which 25 the bars 21, 22 are secured by means of the pins 24. Instead, however, of the bars 7 and 8 I provide curved bars 30, 31, the lower ends of which are connected to the bars 25 by means of the pins 26 described in connection with Fig. 2. The ends of the bars 30 and 31 abut and are connected together by the plate 17' and pins 16' passing through it and openings 32 in the bars 30 and 31. In this construction it will be seen that the 35 mold has an arched roof and both the height and width of the mold may be varied. In order to brace the structure I have shown a pair of bars 33 pivoted together intermediate their ends 34 and adapted to be connected 40 by means of the pins 35 to the openings 26 and also to be connected to the bars 30, 31 by means of the pins 36.

Referring now to the form of construction shown in Fig. 4, the floor section as 45 shown is formed by using a pair of bars 11, 12 adjustably connected together by means of the pin 16, to the upturned ends 13 and 14 of which are connected the ends of the pair of bars 37, 38. In this form of construction the central portion of the roof is formed flat, and in order to effect this I provide a pair of bars 39, 40, provided with perforations 41, their overlapping ends being adjustably connected together, and 50 the opposite ends connected to the bars 37 and 38 by means of the pins 16. In order to brace this structure I have shown the

same as provided with a pair of uprights 42 pinned to the bars 11 and 37 and 12 and 38 respectively, by means of pins 43. 44 are a pair of bars extending from the bars 42 to the overlapping portions of the bars 37 and 13 and 38 and 14, where they are connected together by means of pins 45. 46 is a bar extending between the uprights 42 and held 65 in position by means of the hooks 47, its ends abutting against said uprights.

From the foregoing description of the various forms of my invention illustrated it will be seen that I have provided a mold 70 section which is simple in construction and which may be readily adjusted to various sizes. It is to be understood of course in operation a plurality of these sections are set up, and that they are covered with suitable sheathing of wood or metal, and that the concrete or the like is then tamped into position around the mold so formed in the ordinary manner. After the concrete is set the sections can readily be taken down 80 and removed.

I realize that considerable variation is possible in the details of construction and arrangement of parts without departing from the spirit of my invention, and I therefore do not intend to limit myself to the specific form shown and described.

Having thus described my invention what I claim as new and desire to secure by Letters Patent is:

A mold comprising a pair of members provided with openings in each of the rims, pins adapted to be passed through the openings to join the members adjustably together at one end to form the roof of the construction to be molded, the other ends of said members being down-turned to form the sides of the construction, a second pair of members provided with openings at each of their ends, pins for adjustably connecting the adjacent ends of said members together to form the floor of the construction to be molded, pins for adjustably connecting the ends of the second mentioned members to the down-turned ends of the first mentioned members, and united crossed braces connecting the interior portions of said members to their overlapping lateral portions.

In testimony whereof I affix my signature in presence of two witnesses.

DAVID E. TINGLEY.
